UNITED STATES PATENT OFFICE.

CHARLES H. CUNO, OF MERIDEN, CONNECTICUT, ASSIGNOR TO THE CUNO ENGINEERING CORPORATION, OF MERIDEN, CONNECTICUT, A CORPORATION OF CONNECTICUT.

CIGAR LIGHTER.

Application filed September 18, 1922. Serial No. 587,905.

To all whom it may concern:

Be it known that I, CHARLES H. CUNO, a citizen of the United States of America, residing at Meriden, Connecticut, have invented a new and useful Cigar Lighter, of which the following is a specification.

My invention relates to an electric heating element, which is particularly adapted for use as a cigar lighter.

10 In most instances, in small cigar lighters as heretofore made, it has been impossible to provide a sufficient length of resistance wire in the limited space provided to adapt the device to the heavier voltages, and it has 15 therefore been the practice to insert a rheostat or other resistance in the circuit at a point remote from the device itself.

It is an object of my invention to provide a cigar lighter tip which is so constructed 20 that one sized tip may be adapted to either the lower or the relatively higher voltages, and in which all of the resistance necessary is embodied in the tip itself.

25 A further object is to simplify and improve the construction and serviceability of small heating devices of this character.

In the drawings I have shown, for illustrative purposes only, a preferred form of 30 my invention, in which—

30 Figure 1 is a relatively enlarged end view of a cigar lighter tip embodying features of my invention;

Fig. 2 is a view in side elevation of the form shown in Fig. 1, one quarter being cut 35 away to illustrate the section;

Fig. 3 is a still further enlarged view of parts shown in Figs. 1 and 2, the same being shown as separated;

Fig. 4 is a side elevation, on a relatively 40 reduced scale, of a slightly modified form of the complete article.

In said drawings, 5 indicates a body member of insulating material, such as porcelain or lava. This piece is generally cylindrical 45 in form. The front end of the body is recessed, as indicated at 6, (Fig. 3), and the edge of the recess is preferably undercut to form an inwardly projecting flange or lip 7.

The body 5 has a surrounding groove 8 in its side, for receiving a part of the resistance element of the device. Suitable wire 50 passages may be provided. In the form shown a central passage 9 extends longitudinally through the body 5, while in the

55 outside of said body there is a longitudinally

disposed slot 10. The rear end of the body has a projecting boss 11, through which the passage 9 extends.

12 indicates a metal ferrule for enclosing at least a part of the base. This ferrule has 60 an end aperture 13 through which the boss 11 extends. The upper edge of the ferrule in the completed device may be beaded over into the groove 8, as indicated at 14, to hold the ferrule in place. 65

A heating element in the form of a flat coil of resistance wire 15 is positioned within the end recess 6, and the outside convolution of said coil preferably extends into the undercut portion and beneath the lip or flange 70 7, so as to assist in holding the coil in place. The inner end of the heater coil extends through the central passage 9 and, in the form shown, is embedded in a center soft metal terminal 16 at the end of the boss 11. 75 The opposite end of the heating coil extends downwardly through the portion of the slot 10 above the groove 8 and, when more resistance is desired than is furnished by the heater coil, it may be wound one or more 80 times around the body in the groove 8. This end of the resistance wire is electrically connected to the ferrule 12 and, in the form shown, this end extends through a part of the slot 10 to the base of the ferrule, where 85 it is embedded in the soft metal or solder 17.

The modified form shown in Fig. 4 is substantially the same as the form heretofore described, except that the end of the ferrule extends upwardly, so as to substantially 90 cover the groove 8, and an intermediate portion of the ferrule may be swaged or beaded in, as indicated at 18, so as to hold the ferrule on the body.

The tip or plug may be thrust into any 95 suitable well known receiving socket, and the usual means, such as the pins 19, may be provided for locking the plug in place. The receiving socket for the plug shown would, of course, have the usual contacts 100 for making electrical connection with the resistance coil, as is common in such sockets.

With an arrangement of parts such as described it is possible to make the tip or plug of small size, and by varying the 105 amount of resistance wound around the side of the body, a tip designed for any desired voltage may be produced. Cigar lighters are used quite extensively on automobiles, where the batteries commonly supply cur- 110

rent at six or twelve volts, and for such voltages my present form of cigar lighter is admirably adapted. It is apparent, however, that the adaptability of the device is not limited to any specific range of voltage.

In the preferred form the surrounding groove 8, which is designed to receive what I may term the resistance coil, is preferably of annular form and wide enough to take 10 the desired number of turns of wire to furnish the needed length of resistance wire when the device is to be used with the higher voltages.

While I have described specific forms of 15 my invention, I do not wish to be limited thereto, since various changes may be made within the scope of the appended claims. For example, ribbon or other form of resistance element might be substituted in 20 some instances for round wire. Accordingly, it should be understood that I am using the term "wire" in a broadly descriptive sense. I have likewise used the term "coil" in a broadly descriptive sense to include a grid or other forms of heating or 25 resistance element.

I claim:

1. In a cigar lighter, an insulating body member having a recessed front end and 30 having a boss at the rear end, said body having a side groove therearound and having longitudinally-extending wire passages from the front to the rear end, a substantially flat coil of resistance wire positioned 35 in the recess in the front end to form a heater coil, one end of said resistance wire passing to the rear of said body and being electrically connected to a terminal at the end of said boss, said resistance wire being 40 also wound about said body and positioned in said side groove to form a resistance coil, and a metallic ferrule fixed on the side of said body, the other end of said resistance wire being electrically connected to said 45 ferrule.

2. In a device of the character described, an insulating body member having a recessed front end and a groove surrounding the body at the rear of the front end, said 50 body having a substantially central passage therethrough and a longitudinal slot in the side thereof, a resistance element in the form of a heater coil in the recess in the front end of said body, one end of said 55 resistance element extending through said passage and terminating in a terminal in rear of said body, the other end of said element forming a resistance coil wound about said body and positioned in said 60 groove, and a metallic ferrule surrounding the side of said body and having a portion extending into said groove for securing the ferrule and insulating body together, the other terminal of said resistance element being electrically connected to said ferrule.

3. In a device of the character described, a body of insulating material having a recess in the front end, the outer portion of said recess being undercut to form an overhanging lip, and a substantially flat resistance coil in said recess, the outer convolution of which extends beneath said lip, the ends of said resistance element passing rearwardly of said front end to be electrically connected to terminals. 70

4. In a device of the character described, an insulating body member having a side groove extending there-around, a resistance element including a heating member positioned on the front end of said body, and a 80 resistance member positioned in said side groove, the ends of said resistance element passing to the rear of the side groove for connection to terminals.

5. In a device of the character described, 85 an insulating body member having a side groove extending there-around and also having longitudinal passages therein, and a heater of coiled resistance wire positioned on the front end of said body, one end of said wire being wound around the insulating body and positioned in said side groove, both ends of said wire being also positioned in said longitudinal passages and extended rearwardly to terminals. 90

6. In a device of the character described, an insulating body member having a recessed front end and a boss on the rear end, a metallic ferrule enclosing the rear end of said body and having an aperture through 100 which said boss passes, a heating coil in the recessed front end of said body member, the ends of said coil being electrically connected to terminals.

7. In a device of the character described, 105 an insulating body member, a heating coil on one end of said body, and a resistance coil on the side of said body and removed from said heating coil, said coils being in series, with terminals for the ends of said coils.

8. In a device of the character described, an insulating body member having a shoulder thereon, a metallic ferrule on said body and being locked to said shoulder for holding the body and ferrule together, a heating element on one end of said body, and a resistance on the side of said body in series with said heating element, one end of said resistance element being electrically connected to said ferrule. 115

9. As an article of manufacture, an insulating body member having wire clearance passages extending longitudinally thereof, and also having an annular groove there-around in the side thereof, the front end having a coil-receiving recess therein. 120

10. As an article of manufacture, an insulating body member having a central wire passage extending therethrough and a 130

groove extending there-around, said groove being in communication with the front end of said body member.

11. As an article of manufacture, a substantially cylindrical insulating body member having an annular groove therearound intermediate the ends thereof, said body having a passage extending longitudinally thereof and intersecting said groove, and 10 having another passage extending longitudinally thereof at about the center of said body.

12. An insulating support for electric cigar lighters and the like, comprising a body member of insulating material, said body member being shaped at one end to support a length of resistance wire for heat-

er service, the side of said body member having a recess therein to receive an additional length of said resistance wire for resistance service. 20

13. In a device of the character described, an insulating body member, a heating element mounted on said body, and a resistance element also mounted on said 25 body and in series with said heating element.

14. As an article of manufacture, an insulating body member for electric cigar lighters and the like, said body member 30 having a longitudinal passage therein and having a recess therein for receiving the resistance element.

CHARLES H. CUNO.
